UNITED STATES PATENT OFFICE.

AUGUST SUNDH, OF HASTINGS-UPON-HUDSON, NEW YORK.

HINGE MECHANISM.

1,155,452.

Specification of Letters Patent.

Patented Oct. 5, 1915.

Application filed October 8, 1912. Serial No. 724,508.

To all whom it may concern:

Be it known that I, AUGUST SUNDH, a citizen of the United States, residing in Hastings-upon-Hudson, in the county of 5 Westchester and State of New York, have invented a new and useful Improvement in Hinge Mechanisms, of which the following is a specification.

My invention relates to hinges for use on 10 doors, gates, and the like, and is particularly adapted for use in situations exposed to the weather, and where they receive no particular care. It is a matter of common knowledge that outdoor hinges or hinged gates 15 seldom work perfectly. This is due largely to inefficient lubrication, and because the hinges, springs, and other mechanism are subjected to the elements and rust and wear rapidly, and also become clogged up with 20 mud, ice, etc.

An object of my invention is to overcome these objections, and provide an automatic self-closing gate having a hinge inclosed in a casing which forms an oil reservoir so 25 constructed as to prevent rust, or the access of water, dirt, ice, or anything to interfere with the perfect working of the mechanism.

Other objects of the invention and the exact nature thereof will appear hereinafter.

30 Referring to the accompanying drawings, Figure 1 is a sectional elevation view of hinge mechanism constructed in accordance with my invention, and also showing a portion of a gate attached thereto; Fig. 2 is a 35 sectional elevation view of the hinge mechanism taken on a plane at right angles to that of Fig. 1; Fig. 3 is a sectional view as indicated by the line 3—3 on Fig. 2; Fig. 4 is a sectional view as indicated by the line 4—4 40 on Fig. 1; Fig. 5 is a view showing a gate with my improved form of hinge attached thereto; Fig. 6 is a similar view showing a modified arrangement for attaching the gate to its support.

45 The gate G, as shown in Fig. 5, is hinged to a gate post 1 by means of the hinge mechanism A, mounted on the upper end of the post 1 and a lower hinge 2; the latter is in the form of a strap or heavy band loose on 50 the post and riveted or otherwise secured to the gate. This arrangement permits the gate to move up and down freely, as herein set forth. A dummy A', corresponding in outward appearance to the device A may be 55 mounted on the opposite gate post.

The hinge mechanism A as shown in de-

tail in Figs. 1 and 2, comprises a stationary member 3, the upper portion of which is in the form of a cylindrical receptacle 4. Depending from this receptacle is an extension 5 adapted to enter the hollow post 1. Ribs 6 formed on the extension 5, have a tight fit in the post and secure the member 3 rigidly in position. These ribs may be of sufficient depth to slightly spring the post when 60 driven into place. Extending upward within the receptacle is a tubular projection or sleeve 7. The opening through the extension 5 is continued downward into the projection 7, as shown, and forms a cylinder 70 or socket to receive a vertical pivot pin or pintle 8. This construction provides a long vertical bearing surface between the hinge members, which reduces wear to a minimum and prevents the gate from sagging. Rigidly 75 secured to the pintle 8 is a movable hinge member 9. The latter is in the form of a hollow cylinder or sleeve with a portion cut away to form inclined bearing surfaces 10. The latter coöperate with an anti-friction 80 roller 11 mounted for rotation on a pin 12. Said pin is threaded into the wall of the oil chamber or receptacle 4, and also has a bearing in the extension 7. The roller 11 is frustoconical in shape so as to present an inclined bearing surface, on which the inclined surfaces 10 of the movable hinge member are adapted to roll. The surfaces 10 are substantially spiral or helical, so that the pitch is uniform throughout. Mounted 85 on the hinge member 9 is a protective device 13 forming a cap or cover for the receptacle 4, and parts contained therein. An outer flange 14 extends downward outside of the oil chamber 4, and an inner annular flange 90 15 extends downward within the oil chamber. The flange 15 forms a squared opening 16 with its sides flaring outwardly and downwardly to receive the upper squared end 17 of the rotary hinge member. It will 95 100 be observed that the coöoperating surfaces of the parts 15 and 17 are somewhat divergent to permit a limited swinging movement of the member 13 in the plane of the gate to accommodate the latter if the hinges are not 105 in exact vertical alinement. This adjustment is preferably permitted only in one direction; the bearing surfaces at right angles being preferably a close fit, as indicated in Fig. 4. The member 3 may be provided 110 with an extension 20 forming a socket to receive a section 21 of the fence. The oil

casing is adapted to contain a suitable lubricating oil which when the member 9 is in its lowered position completely covers the bearing surfaces 10 and 11. The pintle 8, which forms a pivot member is adapted to rotate freely and also to have a vertical movement in the cylindrical opening through the parts 5 and 7. The groove or recess 22 extends from the lower end of said rod upward to a point beyond the upper end of the projection 7. The purpose of this groove is to permit the escape of oil from the lower end of the cylinder as the rod descends, and to permit the entrance of oil as the rod is lifted. Said opening may be of such size as to throttle the fluid more or less as the gate swings to a closed position, and thereby effect a dashpot action, preventing too great an acceleration of the gate as it swings by gravity to its closed position. A bracket 24 preferably cast integral with the cover member 13 forms a rigid connection between the latter and the gate.

The operation of my improved hinge mechanism will be apparent without any extended explanation. As the gate is swung open in either direction, the hinge member 9 is compelled to rotate with the gate and the inclined surface 10 rides up the roller 11, thereby lifting the gate in a vertical direction through a distance proportional to its swinging movement. When the gate is released its weight carries it downward and the inclined bearing surface 10 causes it to swing to closed position, where it is automatically fastened by a latch device 23. The latter is preferably constructed in accordance with my invention as fully set forth in my co-pending application for patent on a latch, filed of even date herewith. As shown in Fig. 1 the gate and moving parts carried thereby swing about a vertical axis extending through the center of the post 1.

In the arrangement shown in Fig. 6 the hinge devices A are provided both at the top and near the bottom of the gate. In this instance the brackets 25 are used to attach the hinges to the gate post.

As the hinge mechanism is fully inclosed and the relatively movable contacting surfaces are kept in an oil bath and continually lubricated, a smooth, reliable and efficient action of the mechanism is insured. The parts are fully protected against the entrance of dirt, ice, snow or foreign substances of any kind. They are also fully protected against rust. The mechanism therefore does not quickly get out of order as do the usual constructions in use at the present time.

Both the constructions herein disclosed are in public use at the present time and giving entire satisfaction. It will be understood that various modifications in the details of construction and arrangement of

parts might be made without departing from the spirit and scope of my invention. I wish therefore not to be limited to the precise structures herein disclosed, as the invention comprehends all such modifications as come within the scope of the appended claims.

What I claim is:—

1. The combination of a support, a stationary hinge member carried thereby and formed with an oil chamber, an anti-friction bearing device in said chamber, a movable hinge member rotatable about the vertical axis and having an inclined surface coöperating with said anti-friction bearing device, whereby said member is raised and lowered as it is rotated, and a gate supported and rotatable with said movable member.

2. The combination of a gate adapted to be swung in either direction from a closed position, a hinge member supporting the gate, an oil reservoir containing said hinge member, the latter being rotatable horizontally, and a roller on which said member is supported, the bearing surface of said member being formed to cause said member to move vertically when the gate is swung in either direction from a closed position, whereby the weight of the gate operates to make the gate self-closing when opened in either direction.

3. The combination of a gate post, hinge mechanism located on top of the post and comprising a pintle extending vertically downward within the post, a gate supported by said mechanism and having its axis of movement within the said pintle, said mechanism comprising a bearing located laterally beyond said pintle to support the weight of the gate, and a member to swing with the gate and having an inclined bearing surface also located laterally beyond the pintle to ride on said first named bearing and thereby cause the gate to ride up and down as it swings, said pintle forming a means to receive the lateral strain or pull of the gate while free from the downward pull or weight of the gate.

4. The combination of a gate post, a stationary hinge member mounted on top of the post, a movable hinge member coöperating with the stationary member and having its axis of movement in line with the post, one of said members comprising a vertical pintle, the other member having a vertical socket to receive the pintle, an anti-friction roller mounted on said last named member laterally beyond said socket and pintle and rolling on an inclined surface of the member comprising said pintle, and a closure supported by the said movable member and forming a cover for the hinge, said pintle forming a means to receive the lateral strain or pull of the gate while free from the downward pull or weight of the gate.

5. The combination of a stationary hinge member forming a receptacle adapted to contain lubricating oil, a coöperating movable hinge member, and a cover for the said hinge member and receptacle, said cover carried with the movable hinge member and formed with a downwardly extending flange within which the receptacle projects.

6. The combination of a hinge, an inclosing receptacle adapted to contain a lubricant, a cover member formed with inner and outer depending annular flanges forming an annular recess into which the upper portion of the receptacle extends.

15 7. In a hinge, the combination of coöperating hinge members, one of said members having formed therewith a receptacle for a lubricant, a roller carried by said member within said receptacle and having a stationary bearing in said receptacle, the other member having an inclined surface to ride on said roller, and means to confine the movement of the latter member to a combined vertical and rotary movement.

25 8. In a gravity operated hinge, the combination of a bearing member, a coöperating hinge member rotatable about a vertical axis in either direction from a central position in which it is normally at rest, said rotatable member supported and arranged to ride on said bearing member, and having bearing surfaces inclined downwardly and outwardly in opposite directions from said bearing member when the rotatable member is in said central position, so that a vertical upward movement is imparted to the rotatable member as it rotates in either direction from said central position, and a pintle carried by one of said members, the other member being formed with a socket to inclose and form a bearing in which the pintle reciprocates and rotates, said pintle forming a means to receive the lateral strain or pull of the gate while free from the downward pull or weight of the gate.

9. The combination in a gravity operated hinge, of a stationary member forming a receptacle for a lubricant, an anti-friction roller having a stationary bearing in the receptacle, a rotatable member formed with downwardly inclined diverging faces adapted to coöperate with said roller, and a pintle carried by the rotatable member, said stationary member being formed with a socket in which the pintle reciprocates and rotates.

10. The combination of a receptacle containing a lubricating fluid, a hinge member, means to impart a combined rotary and vertical movement to said member, a vertical cylindrical pintle carried by said member, a socket in said receptacle and in which the pintle has a close bearing fit, said pintle having a groove in its surface for the passage of the lubricant to and from the socket as the

pintle moves therein, said hinge member surrounding said socket and movable up and down in the said receptacle, said groove being sufficiently restricted to materially restrict the flow of the lubricant from the socket as the hinge member and pintle are lowered, and thereby govern the speed of the hinge member.

11. In a gravity operated hinge, the combination of a rotary hinge member, an inclined cam to impart a vertical movement to said hinge member as it rotates, a vertical pivot pin or pintle carried by said hinge member and extending downward therefrom within said cam, a receptacle adapted to contain a lubricating fluid, and a socket for the pintle, said inclined cam located outside of and surrounding said socket and pintle, the pintle communicating with the receptacle through a restricted passage causing a materially restricted flow of the lubricating fluid from the socket, said restriction being sufficient to act as a dash pot and thereby govern the speed of the hinge member.

12. The combination of a gate post, a hinge member carried thereby, a coöperating rotary hinge member, a gate, and a connecting device between the gate and rotary hinge member, adapted to have a limited swinging movement relative to said rotary member, said movement being about an axis perpendicular to the axis of rotation of said rotary hinge member.

13. The combination of a gate post, a hinge mounted thereon and comprising a gravity operated member movable vertically and rotatable about a vertical axis, said member having a squared head, a gate, a connecting device between the gate and said member and having a socket formed to receive said squared head, said head and socket being formed to permit a limited relative movement in the plane of the gate.

14. The combination of a post, a hinge carried thereby comprising a hinge member adapted for vertical and horizontal movement and being located on top of the post and having a downwardly extending pintle, and coöperating hinge member comprising an integral socket extending downwardly within the post and forming a guide for said pintle.

15. The combination of a post, a hinge member secured in the post, said hinge member having a vertical guiding socket within the post, another hinge member adapted for vertical and horizontal movement and having fixed thereto a pintle pivotally supported and guided in said socket, and a gate supported by said hinge.

16. The combination with a post having a vertical opening therein, of a hinge member supported on the post and abutting against the top of the post and formed with an integral socket extending downward within

said opening, and a second hinge member adapted for a combined vertical and horizontal movement, and having a pintle pivotally supported and guided in said socket during said movement and forming with said socket a dashpot to control the speed of the moving hinge member.

17. The combination of a post, a stationary hinge member seated therein and formed with an opening or socket, a second hinge member rotatable about a vertical axis and also movable vertically, said second member having an extension fitted and guided in said socket, an antifriction device between said members, and lubricating means for said extension and antifriction device.

18. In a gate hinge, the combination of an anti-friction bearing, a hinge member rotatable about a vertical axis and riding on said bearing, said member also having a vertical movement as it rotates about its axis, an inclosure for said anti-friction bearing and said hinge member, lubricating means in said inclosure, and a covering for said inclosure for protection from snow or ice.

20

25

In testimony whereof, I have signed my name to this specification in the presence of two subscribing witnesses.

AUGUST SUNDH.
